UNITED STATES PATENT OFFICE.

WILLIAM K. HOLMAN, OF PHILADELPHIA, PENNSYLVANIA, ASSIGNOR TO A. J. HOLMAN & COMPANY, OF PHILADELPHIA, PENNSYLVANIA, A. FIRM.

FILING-CASE.

No. 884,659.

Specification of Letters Patent.

Patented April 14, 1908.

Application filed September 27, 1907. Serial No. 394,796.

To all whom it may concern:

Be it known that I, WILLIAM K. HOLMAN, a citizen of the United States, residing in the city of Philadelphia, State of Pennsylvania, 5 have invented certain new and useful Improvements in Filing - Cases, of which the following is a full, clear, and exact description, reference being had to the accompanying drawings, forming a part of this specification.

10 My invention relates to that class of filing devices comprising an inclosing casing with a hinged lid, adapted to contain interiorly a paper file with a series of leaves or sheets of 15 paper thereon; and my improvement in this class of device has for its object the provision of a new form and character of file which while enabling the several sheets or any of them in the series to be more readily removed 20 and replaced than heretofore, will also coact with the inner walls of the casing to removably form a part thereof when the said file and casing are assembled in operative relation.

25 To these ends my invention consists in the combination with a filing case consisting essentially of a rectangular box-like structure, preferably with a hinged lid, and having two of its oppositely-disposed upright walls recessed to form opposite semi-cylindrical vertical grooves, of a removable file consisting of a wire rod bent in its length to form one or a pair of filing hooks, preferably of a 30 specific character as hereinafter stated, the 35 respective terminal ends of said rod being bent upward to form resilient ends adapted to spring automatically into the vertical grooves in the side walls of the casing and to be readily removed therefrom when it is 40 desired to remove the file of papers or other articles from time to time.

In the accompanying drawings illustrating my invention:—Figure 1 is an elevation in perspective of the filing case, with the file, 45 containing a layer of papers, in place therein. Fig. 2 is a detached perspective view of the file, with a layer of papers filed therein; and Fig. 3 is a like view of the file detached. Fig. 4 is a plan view, partly in section; Fig. 5 is a 50 vertical section taken through the longitudinal center of the device as shown in Fig. 4; and Fig. 6 is a like vertical section taken through the lateral center thereof.

55 Referring now to Fig. 1 of said drawings, the filing case is constructed as usual in the

form of a shallow rectangular box having its rear end end wall 1 hinged to the base wall so as to drop downward, and its lid 2 is preferably hinged to a narrow and fixed top wall or cover 3 so as to swing upward. A spring button 4 serves to detachably connect the hinged portions 1 and 2. Otherwise than as stated, the filing case consists of a base wall 5, a rear wall 6, and oppositely-disposed vertical side walls 7, 7, and these latter near their rear- 60 ward end and preferably beneath the narrow fixed top wall 3, are vertically recessed at oppositely-disposed points to form a pair of semi-cylindrical vertical grooves 8, 8, to receive, removably, the spring ends of the pa- 65 per file hereinafter described.

The file proper is shown in elevation in Fig. 3, and referring thereto, it will be seen to consist of a wire rod 10 adapted to be horizontally disposed in the casing, and which, 70 from end to end between the bases of its spring ends conforms in length with the distance between the semi-cylindrical grooves 8 in the filing case. The rod 10 has its extreme ends bent upward to form spring 80 catches 9, 9, and these being resilient, will spring into place in and be readily removable from the semi-cylindrical grooves 8, 8, in the filing case, by a gentle manual pressure employed in operatively assembling or dissociat- 85 ing said elements. In the length of the rod and adjacent to the spring ends is a pair of integrally formed filing hooks, adapted to removably and replaceably hold a series of 90 sheets of paper or pasteboard 12, which are appropriately punched out at 13 to admit the hooks, to pass through them and hold the papers in place thereon and in series. These hooks consist of two vertical bends 15, 15, followed by a short horizontal connecting 95 bend 16; and in order to be able to better apply a manual pressure to remove the spring catches 9 from their seats in the grooves 8 of the filing case, the bends 15 of the filing hooks are slightly separated from each other and 100 are in the same vertical plane with the spring ends 9 while a rearward bend is preferably given to that part of the connecting rod 10 which is between the hooks, when a pair of 105 hooks is employed; it is obvious however that a single long hook having like character of bends may be employed instead of a pair of hooks.

The operation of the device is such that a file or series of papers or cards, punched at 110

13, are held in spaced relation, laterally, by the upright spring ends 9 of the file (see Fig. 2). The horizontal bend 16 prevents vertical displacement of the filed papers, while freely 5 permitting assembling them in series as shown, with perfect freedom to space them vertically in relation to each other. When the papers or cards are so placed on the file, (as in Fig. 2), and the latter inserted in the 10 casing, a slight manual pressure against the front of the hooks 15, will cause the spring catches 9, 9, to pass automatically into locked position in the grooves 8, 8, of the filing case; while, when it is desired to remove 15 the pile of filed papers, a slight manual pressure on the sides of the hooks 15, 15, by squeezing them together, will act on the integral spring catches 9, 9, to release them from engagement with the semi-cylindrical groove 20 8 in the opposite walls 7, 7, of the filing case.

My device is simple, economical in construction, and has been found in practice to possess decided utility and many advantages over devices of its class now in use.

Having thus described my invention, I claim as new and desire to secure by Letters Patent:—

1. A filing case comprising a containing box having oppositely-disposed vertical walls 36 provided with open vertical grooves in combination with a filing rod provided intermediate its ends with a filing device and having each of said ends bent upward to form spring catches adapted to spring automatically into 35 the vertical grooves in the filing case when said parts are operatively assembled.

2. A filing case comprising a containing box having oppositely-disposed vertical walls provided with open vertical grooves, in combination with a filing rod having each of its 40 opposite ends bent upward to form a pair of oppositely-acting spring catches adapted to coincide removably with said vertical grooves in the casing, said rod being provided with a pair of integrally-formed filing hooks, each 45 consisting of two separated vertical bends connected by a short horizontal bend, the body of the rod between said hooks being bent to lie in a rearwardly parallel plane.

3. A filing case comprising a shallow containing box of substantially rectangular outline, having a front wall hinged to its basal wall a narrow and fixed top wall over its rearward portion, and a lid hinged thereto and a pair of oppositely-disposed vertical walls provided near the rearward end and beneath 55 said fixed top with open vertical grooves, in combination with a filing rod adapted to be disposed horizontally in said casing, said rod having integrally formed therein a pair of 60 filing hooks and having spring ends adapted to removably coincide with said grooves in the casing when the file and casing are operatively assembled.

In testimony whereof, I have hereunto affixed my signature this tenth day of September A. D. 1907.

WILLIAM K. HOLMAN.
